CONTROLLING AND SENSORY SYSTEM

Samuel E. Adair, Chicago, Ill., assignor, by mesne assignments, to Bendix Radio Corporation, Baltimore, Md., a corporation of Delaware

Application November 20, 1937, Serial No. 175,644

6 Claims. (Cl. 179—100.4)

This invention relates to controlling and sensory systems and more particularly to systems in which a record for the reproduction of a sensory effect carries thereon an operating component to operate a device or series of devices.

One object of the invention is to provide a controlling and sensory system in which the sensory effect and the devices to be controlled are correlated to provide automatically for a predetermined time relationship in their operation with very little possibility of confusion.

Another object of the invention is to provide a controlling and sensory system in which devices to be controlled are normally held inactive by a controlling component and are actuated by interruption of such component. Preferably the controlling component is reproduced from a record which may also carry a sensory component to give any desired sensory effect.

Another object of the invention is to provide a novel controlling method particularly adapted for use with a sensory system.

Other objects, advantages and novel features of the invention will become apparent from the following description of the illustrative embodiment shown in the accompanying drawing, in which:

Figure 1 is a diagrammatic representation of a controlling and sensory system embodying the invention;

Figure 2 is an enlarged diagrammatic representation of the operating frequency component of the record;

Figure 3 is an enlarged diagrammatic representation of the sensory component;

Figure 4 is an enlarged diagrammatic representation of the resultant sensory track; and

Fig. 5 is a diagrammatic representation of one method of producing the record.

The invention is illustrated in Fig. 1 as embodying a disc record 10 having recorded thereon some sound or other sensory effect which it is desired to reproduce and an operating component 12 superimposed thereon.

The system is generally similar to that described and claimed in the co-pending applications of John E. Jenkins and Samuel E. Adair, Ser. No. 690,656 filed September 23, 1933, and Ser. No. 200,652, filed April 7, 1938.

An electrical pickup 16 may be employed to convert the mechanical vibrations on the record to electrical oscillations which may be amplified by an amplifier 18 and reproduced through a loudspeaker 20. A filter 22 may, if desired, be employed in this circuit to filter out the oper-

ating component so that it will not be reproduced by the loudspeaker.

A device operating circuit, in parallel with the above circuit may consist of a filter 24 connected to the pickup 16. The filter 24 is so constructed as to pass only the device operating component. The other end of the filter is shown connected to an amplifier 28 which in turn delivers the amplified device operating component to a relay 30. This relay may, if desired, be of the retuned type. The relay 30 may be adapted to operate any device or series of devices and is illustrated as controlling a continuous film picture projector 32 more completely described below, and described and claimed in the previously mentioned copending applications.

As shown in Fig. 4 the record 10 consists of a single recorded track incorporating both a normal sound recording 14 (Fig. 3) which shall be called the sound track, and a device-operating recording 12 (Fig. 2), which shall be called the operating component; that is to say the normal sound track 14 is combined with the operating component 12, so that record 10 consists mainly of recorded vibrations 13 (Fig. 4) comprising the resultant of the sound track 14 and the operating component 12.

According to the present invention, the operating component consists of a low frequency sound oscillation present at every portion of the sound track except at that portion in which it is desired to operate or start to operate a device such as the continuous film projector 32.

It can readily be seen that there is very little possibility of the normal sound track having an oscillation of exactly the same frequency and in exactly the same phase relationship as that of the operating component at the portion of the sound track in which the operating component is absent. This insures that the device to be operated such as the projector 32, will be operated only at the proper time.

The record 10, may be prepared in any suitable manner. One desirable method being illustrated in Fig. 5 and including a suitable recorder 45 100, a device such as microphone 102 for delivering to the recorder the normal sound vibrations such as the speech, music or other sound it is desired to reproduce, and a device for delivering to the recorder the device operating frequency. 50 The device for delivering the device operating frequency is shown as an oscillator 104 and leads 106 having a normally closed switch 108. The leads 106 connect the oscillator to the recorder so that the recorder can deliver to the record 55.

the device-operating component as long as the switch 108 remains closed. This switch may be opened at the time during the recording of the normal sound track at which it is desired to operate the device 32.

It is to be understood that the record 10 may be of any suitable type known in the art, that is, it may be a groove formed in a cylinder or disc, as shown, a photographic record on a film, or a magnetic record on wire.

The device operating circuit illustrated in Figure 1 comprises a filter 24, connected to the pickup 16. The filter 24 is so designed as to permit only those oscillations to pass which correspond in frequency to that of the device operating component.

The filter 24 may be connected to an amplifier 28, which in turn delivers the amplified operating current to the relay 30. Whether the amplifier 28 is necessary or not depends upon the sensitivity of the relay.

The filter 24 need not be employed if the relay 30 is of the tuned type.

The relay 30 is shown normally biased by spring 31 in switch closed position, but the operating component being present at all times to energize relay 30 except when it is desired to close the relay switch, the switch is held open until that particular time at which the operating component is absent on the record.

What is claimed is:

1. In a controlling and sensory system, a record having recorded thereon a sensory component, a control component modulating said sensory component throughout the greater part of said record, an unmodulated portion of said sensory component located at a predetermined point along said recording, means for converting said recorded components into electrical impulses, and means responsive to said impulses for instituting a control function upon the occurrence of said unmodulated portion of said sensory component.

2. In a controlling and sensory system, a record having recorded thereon a sensory component, a control component modulating said sensory component throughout the greater part of said record, an unmodulated portion of said sensory component located at a predetermined point along said recording, means for converting said recorded components into electrical impulses, a control circuit having a source of current, and means for preventing flow of current in said circuit during the period in which said sensory component is modulated.

3. In a controlling and sensory system, a rec-

ord having recorded thereon a sensory component, a control component modulating said sensory component throughout the greater part of said record, an unmodulated portion of said sensory component located at a predetermined point along said recording, means for converting said recorded components into electrical impulses, a control circuit having a source of current, and means for maintaining said circuit open during the period in which said sensory component is modulated.

4. In a controlling and sensory system, a record having recorded thereon a sensory component, a control component modulating said sensory component throughout the greater part of said record, an unmodulated portion of said sensory component located at a predetermined point along said recording, means for converting said recorded components into electrical impulses, means for selecting impulses corresponding to said control component from said electrical impulses, and a control relay actuated in response to said selected impulses and for the duration thereof.

5. In a controlling and sensory system, a device to be operated by said system, a record having recorded thereon a sensory component, a control component modulating said sensory component throughout the greater part of said record, an unmodulated portion of said sensory component located at a predetermined point along said recording, means for converting said recorded components into electrical impulses, and means responsive to said impulses for operating said device upon the occurrence of said unmodulated portion of said sensory component.

6. In a controlling and sensory system, a device to be operated by said system, a record having recorded thereon a sensory component, a control component modulating said sensory component throughout the greater part of said record, an unmodulated portion of said sensory component located at a predetermined point along said recording, means for converting said recorded components into electrical impulses, means for reproducing said sensory component being connected to said conversion means, means for selecting impulses corresponding to said control component from said electrical impulses, and means responsive to said selected impulses for maintaining said device inoperative, said means permitting operation of said device upon the occurrence of said unmodulated portion of said sensory component.

SAMUEL E. ADAIR.
